UNITED STATES PATENT OFFICE.

LEONARD L. DAVIS, OF SPRINGFIELD, MASSACHUSETTS.

BIT-STOCK.

SPECIFICATION forming part of Letters Patent No. 432,180, dated July 15, 1890.

Application filed January 13, 1890. Serial No. 336,757. (No model.)

To all whom it may concern:

Be it known that I, LEONARD L. DAVIS, a citizen of the United States, residing at Springfield, in the county of Hampden and State of Massachusetts, have invented new and useful Improvements in Bit-Stocks, of which the following is a specification.

This invention relates to bit-stocks, and has reference particularly to an improved equipment of jaws and shank-socket therefor adapted to receive the engagement therewith of said jaws; and the invention consists in the peculiar construction and arrangement of said parts, all as hereinafter fully described, and pointed out in the claim.

In the drawings forming part of this specification, Figure 1 is a side elevation of the lower end of the bit-stock and a longitudinal section of the tool-socket and its screw-sleeve, showing therein, in edge view, the jaws of the implement, all embodying my improvements. Fig. 2 is a cross-section on line 2 2, Fig. 1. Fig. 3 is a perspective view of one of the jaws. Fig. 4 is a perspective view of a jaw of a slightly-modified construction.

In the drawings, A is the lower end of a bit-stock of the usual metallic construction, and B is the tool-socket exteriorly screw-threaded and having the jaw-operating sleeve D screw-

ing freely thereon in the usual manner. Each of the two jaws *h* consists of a head 3, suitably grooved to grasp a tool placed between them, and a spring-shank 4, having a stud 5 formed therein or rigidly attached thereto, the sides of which are plain or smooth, which is located near one end of said spring-shank extending at right angles to the side thereof. The said tool-socket has the usual longitudinal recess 6 therein to receive the shank of the tool that may be held and turned by the bit-stock, and in opposite sides of said socket B are formed two longitudinal grooves 7 for the reception therein of the said jaws *h*, wherein they occupy the positions shown in Fig. 1, and in said socket at the inner end of said grooves is smoothly bored a cylindrical socket to receive the said studs 5 on the shanks of the jaws *h*, as clearly shown in said last-named figure. The bottom of each of said grooves 7 nearly from the inner to the outer end thereof is inclined toward the axis of the socket B, said inclination beginning a little

forward of the sockets which receive the studs 5 of the jaws *h*, in order to form at the side of each of said sockets a salient point *x*, on 55 or across which that part of the spring-shank 4 of the jaw *h* near its stud 5 may bear when the heads 3 thereof are forced toward each other, as below described, and whereby the reaction of the spring-shanks to throw the 60 jaw-heads apart is made more effective. The said screw-threaded sleeve D incloses the said socket B and spring-jaws *h*, as shown, and has a spherical head 8, the inner curved side of which is forced against the heads 3 of 65 the jaws *h*, thereby forcing them together and against the shank of a tool-piece in the bit, thereby holding said tool firmly. Screwing said sleeve outwardly or more or less off from the socket B permits the jaw-heads 3 to spring 70 apart or separate, so that said tool may be removed from the bit.

Bit-stocks which have heretofore been made with jaws embodying spring-shanks forming a part thereof have been held in place on the 75 tool-socket part B by the provision of screws which have been by their shanks passed freely through perforations in the extremities of said jaw-shanks and with a screw engagement into the tapped transverse holes in the 80 tool-socket part of the stock, the heads of the screws having borne upon the outer sides of the jaw-shanks. In the assemblage of the parts of such a bit-stock the turning in of the screws to hold the jaws on the socket part 85 is tedious and requires considerable time. While under this invention the smooth stud affixed as one onto the spring-jaw by one movement may be readily inserted in the smooth-bored socket therefor in the socket 90 part B. Of course the spring-shank may be as readily detached from the said socket part B, and yet when it is engaged therewith its engagement is as efficient as if made with the screws. It will be mentioned that it is deemed 95 undesirable to employ the screws, for a reason further than above stated—namely, such screws are usually machine-made, and in the event of one becoming lost from the bit-stock may not readily be replaced.

Fig. 4 illustrates a jaw having a spring-shank 4, which is made of a separate piece of spring metal and riveted or otherwise similarly fixed thereon. This modification of the

manner of making said spring-jaw, as compared with that shown in Fig. 3, results in the production of a jaw having substantially the same function as that shown in said last 5 named figure; but it is less durable in use and requires more operations in its manufacture, for the jaw shown in Fig. 3 may be made of a single piece of metal by drop-forging it.

What I claim as my invention is—

10. The combination, with the tool-socket part B of a bit-stock provided with the longitudinal depressions 7 7 and the smooth - bored sockets extending laterally and inwardly from

the bases of said depressions, of the jaws *h h*, having spring-shanks, and the smooth studs 15 5 5, formed on and laterally extended from the sides of the shanks, and said studs adapted when the said jaws are in place in their respective depressions 7 therefor to freely enter the said smooth sockets, all substantially as 20 described and shown, and for the purposes set forth.

LEONARD L. DAVIS.
